UNITED STATES PATENT OFFICE.

WILLIAM HINTON, OF HINTON, WEST VIRGINIA, ASSIGNOR OF ONE-HALF
TO GEORGE O. QUESENBERRY, OF SAME PLACE.

NON-REFILLABLE BOTTLE.

SPECIFICATION forming part of Letters Patent No. 658,895, dated October 2, 1900.

Application filed February 10, 1900. Serial No. 4,811. (No model.)

To all whom it may concern:

Be it known that I, WILLIAM HINTON, a citizen of the United States, residing at Hinton, in the county of Summers and State of 55 West Virginia, have invented a new and useful Non-Refillable Bottle, of which the following is a specification.

My invention relates to non-refillable bottles; and it has for its object to produce a bottle in which it is impossible to gain access to the cork without breaking some portion of the locking mechanism, and thereby destroy the package in which the original goods were put upon the market, and thus indicating to 15 the purchaser that the contents of the bottle or other package had not been placed therein by the original manufacturer or dealer.

With these objects in view my invention consists in the improved construction and 20 novel combination of parts of a bottle and locking mechanism therefor, as will be hereinafter more fully set forth.

In the accompanying drawings, in which the same reference-numerals indicate corresponding parts in each of the views in which they occur, Figure 1 is a longitudinal sectional view of the neck of a bottle provided with my improved locking mechanism in position to be secured upon the bottle. Fig. 2 30 is a similar view with the locking mechanism in another position. Fig. 3 is a perspective view of the neck of the bottle, and Fig. 4 is an inverted perspective view of the cover or cap.

Referring more particularly to the drawings, 1 indicates the neck of a bottle, which may be of any suitable size and dimensions, the top of which is provided with an annularly-grooved flange or collar 2, the opposite 35 sides of said collar being provided with radial recesses 3. Seated within each of said recesses is a longitudinally-movable lock or key 4, the length of which is substantially equal to the height of the collar 2. A spring 5 surrounds the neck of the bottle, with its upper 45 end bearing against the lower shoulder of the collar 2 and its lower end resting upon a shoulder 6. The lower ends of the keys 4 rest upon the top of the spring and are normally forced upward until the upper ends of 50 the keys stand flush or even with the top of

the neck of the bottle. A cap or cover 7 fits over the top of the bottle and is provided with two inwardly-projecting lugs 8 of substantially the same thickness as the groove in the 55 collar 2, and they are so arranged that when the cap is placed upon the top of the bottle the lugs will enter the recess 3 and will enter the groove in the collar when the cap has been forced inward far enough and is rotated upon 60 the top of the bottle. After the spring has been placed upon the neck of the bottle a cylinder 9, preferably of glass or other suitable material, is slipped over the spring and is of a sufficient length to extend from the 65 shoulder 6 up to the under edge of the cap, and thereby prevent access being had to the keys 4 after the cap has been placed in position upon the bottle.

In using my improved non-refillable bottle 70 the spring is inserted between the collar at the top and the shoulder near the top of the body portion of the bottle, and the keys are loosely placed in the recess 3. The cap is then placed above the top of the bottle, with the 75 projections 8 resting upon the tops of the keys, and forced downward until the projections have been brought to register with the groove in the collar, when the cap is rotated sufficiently to remove the projections from the 80 tops of the keys, when the action of the spring will instantly force the keys longitudinally upward across the mouth of the groove in the collar of the recess. In this position it is evident that it will be impossible to rotate the 85 cap in either direction, so as to bring the projections to register with the recess, and thereby it will be impossible to remove the cap to gain access to the cork of the bottle without 90 breaking some portion of the bottle.

Having thus fully described my invention, what I claim as new, and desire to secure by Letters Patent of the United States, is—

1. In a non-refillable bottle, the combination, with a bottle the neck of which is grooved 95 annularly and provided with longitudinal grooves in position to intersect the annular groove, of longitudinally-movable keys in the longitudinal grooves, a cap provided with inwardly-extending projections in position to enter the annular groove and be locked therein by the keys, substantially as described.

2. In a non-refillable bottle, the combination with a bottle, the neck of which is annularly grooved near its upper end and provided with longitudinal grooves in position to 5 intersect the annular groove, keys in said longitudinal grooves, a cap provided with inwardly-extending projections in position to enter the annular groove and be locked therein by the keys, a spring for holding the keys 10 across the annular groove and a shield around the spring, substantially as described.
3. In a non-refillable bottle, the combination, with a bottle the lower portion of the neck of which is shouldered and the upper 15 end is provided with an annularly-grooved collar, said collar being provided with longi-

tudinal grooves, keys in said longitudinal grooves of substantially the same length as the height of the collar, a spring upon the neck between the shoulder and the bottom of the collar, a cylindrical shield around the spring, and a cap, the flange of which is adapted to rest against the top of the shield when in position, and is provided with inwardly-extending projections adapted to enter the 20 longitudinal grooves and be locked within the annular groove by means of said keys, substantially as described.

WM. HINTON.
